UNITED STATES PATENT OFFICE

144,841

DESIGN FOR A MOTION PICTURE PROJECTING MACHINE

William C. De Vry, Chicago, Ill., assignor to De Vry
Corporation, Chicago, Ill.

Application January 5, 1946, Serial No. 125,292

Term of patent 7 years

(Cl. D61—1)

To all whom it may concern:

Be it known that I, William C. De Vry, a citizen of the United States, and a resident of Chicago, in the county of Cook and State of Illinois, have invented a new, original, and ornamental Design for a Motion Picture Projecting Machine, of which the following is a specification, reference being had to the accompanying drawings, forming a part thereof, and in which:

Fig. 1 is a perspective view of a motion picture projecting machine, showing my new design;

Fig. 2 is a perspective view of the opposite side of the same.

I claim:

The ornamental design for a motion picture projecting machine, as shown.

WILLIAM C. DE VRY.
